UNITED STATES PATENT OFFICE.

THOMAS R. FREEMAN, OF SIOUX FALLS, SOUTH DAKOTA, ASSIGNOR OF ONE-HALF TO WILLIAM D. ROBERTS, OF SAME PLACE.

FURNACE.

SPECIFICATION forming part of Letters Patent No. 480,086, dated August 2, 1892.

Application filed April 21, 1892. Serial No. 430,123. (No model.)

To all whom it may concern:

Be it known that I, THOMAS R. FREEMAN, a citizen of the United States, residing at Sioux Falls, in the county of Minnehaha and State 5 of South Dakota, have invented certain new and useful Improvements in Furnaces; and I do hereby declare the following to be a full, clear, and exact description of the invention, such as will enable others skilled in the 10 art to which it appertains to make and use the same.

This invention relates to stoves and furnaces, and more especially to that class thereof known as "hot-air" furnaces, because its office 15 is to heat air which is subsequently conveyed to the rooms or apartments to be heated.

The object of the present invention is to improve the construction of radiators used in such a furnace to the end that the air will be 20 more thoroughly heated than heretofore, as well as to improve the details of construction of the whole.

To this end the invention consists in a furnace constructed substantially as hereinafter 25 more fully described and claimed, and as illustrated in the accompanying drawings, in which—

Figure 1 is a central vertical section of the entire furnace and casing, the parts being arranged to direct the products of combustion as indicated by the arrows. Fig. 2 is a horizontal section thereof on the line 2 2 of Fig. 1. Fig. 3 is a right-side elevation of the upper portion of the furnace, showing the casing 35 in dotted lines. Fig. 4 is a front elevation of the upper portion of the furnace.

In the said drawings the casing is shown in two parts, the lowermost one 1 having a bottom flange 2, resting on the support, (not shown,) and through which support the cold air is fed to the furnace, as usual, and the uppermost one 2' being connected detachably, as at 3, with the upper edge of the lower part and having the hot-air pipes 4, which lead to 45 the rooms or apartments to be heated, as will be understood. This casing is here shown as of sheet metal, although it may be of masonry, brickwork, or any other material, as preferred. Within the lowermost part 1 is a 50 deflector 5, inclined so as to direct the cold

air toward and against the body of the furnace, whereby it will be heated thoroughly before it passes into the pipes 4.

Supported in anysuitable manner within the casing, as by braces 6, is the ash-pit 7, having 55 the usual door 8, and 9 is the grate having the shaker 10 and located at the bottom of the fire-pot 11.

12 is a small door opening into the fire-pot 11 above the grate, through which door a suitable instrument may be passed for cleaning the grate or other purposes, the front of the fire-pot being cut away, as at 13.

At the upper end of the fire-pot is the heating or combustion chamber 20, connected directly therewith and opening therewith, as shown, this chamber preferably having a convex top 21. From the rear of the chamber 20, near its top, opens the usual exit-flue 22, which leads thence downward through a damper 23 70 to a box 24, and a pipe 25 connects this box directly with the smoke-flue 26 and thence with the chimney. The damper 23 is operated by a handle 23', which leads through the casing about as shown. Depending from the 75 box 24 is the dust-exit flue 27, having a damper 28, operated by a handle 28', leading, also, through the casing and then connecting with the rear of the ash-pit, whereby the dust in the ash-pit during shaking of the grate may 80 be conveyed to the chimney and the draft regulated, all as is now common in furnaces of this character, save, perhaps, in the specific details of construction.

Coming now to the principal part of the invention, 85 30 is a curved shield supported within the chamber 20 and opening therewith over its rear edge 31, while at its front end a hole 32 is formed through the body of the furnace.

33 is what I call the "front radiator," being a 90 curved box, preferably square or rectangular in cross-section and curving around the front of the furnace at its top for about one-third of a circle, as seen in Fig. 2, its supports being bolts, straps, or braces as desired. The extremities of this radiator are closed and beveled, as seen at 34, and just forward thereof small pipes 35 lead downward and rearward to the front ends of the rear radiator 36, the latter being of similar construction, standing 95 100

in a plane below the front radiator, occupying the remaining two-thirds of a circle, and opening into the box 24 at its center. A cleaning-opening 37 is provided opposite the 5 hole 32, whereby the upper radiator and the shieldway may be cleaned, and others 38 are formed in the front ends of the lower and rear radiator for the same purpose with reference thereto, all these openings being suitably closed, as seen, and of course opening through the casing.

40 is the coal-chute, having the door 41, and 42 is a pipe communicating with this chute and opening into the upper radiator, a damper 15 43 being located in this pipe and operated by a handle 43', as seen. The function of this pipe is to draw the dust and gas from the coal-chute when the door is open and coal is being fed to the furnace. At other times the 20 damper 43 is closed, and communication between the chute and the radiator is closed.

With this construction of parts the operation of my improved furnace is as follows: A fire being laid and lighted, the damper 23 is 25 opened and there is a direct draft from the fire-pot through the exit-flue 22, box 24, and smoke-flue 26 to the chimney. The fire will thus start with the best possible draft. After the fire has got well under way the exit-damper 23 30 is closed. This causes the products of combustion to take a course over the rear edge 31 of the shield 30, through the hole 32, dividing and passing to the rear in the upper and front radiator, thence down the two small pipes 35 35 to and into the lower and rear radiator, reuniting in the box 24, and then out the smoke-flue 26 to the chimney. It will be noticed in Fig. 2 that the radiators occupy most all the space within the casing around the body of 40 the furnace. The result is that the cold air rising within the casing is thrown into close contact with these radiators and thoroughly heated before it is allowed to enter the hot-air pipes 4. The small pipes 35, which cause 45 the products of combustion to descend from the front radiator to the rear, somewhat retard their passage through the course provided for them, and hence the metal of the radiators (and of course the surrounding air) is highly 50 heated. The deflector 5, as above stated, throws the cold air against the body of the furnace and warms it to some extent before it reaches the radiators, as will be seen.

All parts of the furnace are preferably of 55 sheet metal, although the materials, sizes, and exact shapes of parts may be changed considerably without departing from the principle of my invention.

What is claimed as new is—

60 1. In a furnace, the combination, with the casing, the hot-air pipes leading therefrom, the furnace-body, a box in rear thereof, and the smoke-flue leading from said box to the chimney, of a shield within the furnace-body, 65 its rear edge standing near the top and rear of said body and its front opening through

said body, a front radiator between the casing and body, curving through about one-third of a circle and communicating at its center with said opening from the shield, a rear radiator 70 similarly located and occupying the remaining two-thirds of a circle, its center communicating with said box, and depending oblique pipes connecting the ends of the front and rear radiators, as and for the purpose set 75 forth.

2. In a furnace, the combination, with the casing, the hot-air pipes leading therefrom, the furnace-body, a box in rear thereof, an exit-pipe connecting the body with said box, 80 a damper in said pipe, and the smoke-flue leading from the box to the chimney, of an opening at the front of said body near its top, a front radiator between the casing and body, curving throughout part of a circle 85 and communicating at its center with said opening, a rear radiator similarly located, occupying the remaining part of the circle and communicating at its center with said box, and depending oblique pipes connecting the 90 ends of the radiators, as and for the purpose set forth.

3. In a furnace, the combination, with the casing, the hot-air pipes leading therefrom, the furnace-body, a box in rear thereof, a 95 dust-exit flue connecting said box with the ash-pit of the body, a damper in said flue, and the smoke-flue connecting the box with the chimney, of an opening in the front of the furnace-body near its top, a front radiator between the casing and body, curving throughout part of a circle and connecting 100 at its center with said opening, a rear radiator similarly located, occupying the remaining part of the circle and communicating at 105 its center with said box, and depending pipes connecting the ends of said radiators, as and for the purpose set forth.

4. In a furnace, the combination, with the casing, the hot-air pipes leading therefrom, 110 the furnace-body, a box in rear thereof, an exit-pipe connecting the body with said box, a damper in said pipe, a dust-exit flue connecting the box with the ash-pit, a damper 115 in said flue, and the smoke-flue connecting the box with the chimney, of a front radiator between the body and casing, curving throughout part of a circle and communicating at its center with the front of the body, and a rear radiator similarly located, occupying the remaining part of the circle, communicating at 120 its center with said box, and connected at its ends with the ends of the front radiator, as and for the purpose set forth.

5. In a furnace, the combination, with the 125 casing, the hot-air pipes leading therefrom, the furnace-body having a convex top, the coal-chute opening into the front of said body and having a door, and the smoke-flue leading to the chimney, of a front radiator 130 curving around the body within the casing and near the top of said body, with which it

communicates at its center, a rear radiator also curving around the body, connected with the front radiator, and communicating with the smoke-flues, a pipe connecting the front 5 radiator with said chute, and a damper in this pipe, all as and for the purpose hereinbefore set forth.

In testimony whereof I affix my signature in presence of two witnesses.

THOMAS R. FREEMAN.
